UNITED STATES PATENT OFFICE.

GEORGE W. BADGER, OF MALDEN, MASSACHUSETTS, ASSIGNOR TO GEORGE P. COX, OF SAME PLACE.

BOOT-TREE.

SPECIFICATION forming part of Letters Patent No. 224,067, dated February 3, 1880.

Application filed November 18, 1879.

To all whom it may concern:

Be it known that I, GEORGE W. BADGER, of Malden, in the county of Middlesex and State of Massachusetts, have invented certain 5 Improvements in Boot-Trees to be used in the manufacture of rubber boots, of which the following is a full, clear, and exact description, reference being had to the accompanying drawings, making part of this specification, in 10 which—

Figure 1 is a side elevation of a boot-tree constructed in accordance with my invention. Fig. 2 is a vertical section through the same. Fig. 3 is a horizontal section on the line xx 15 of Fig. 1. Fig. 4 is a perspective view of the lower end of the leg portion of the boot-tree. Fig. 5 is a perspective view of the foot portion detached.

In boot-trees used in the manufacture of 20 vulcanized-rubber boots, as ordinarily constructed, the lower end of the long screw-bolt by which the leg and foot portions are secured together engages with a flat nut, which is secured within a recess in the foot portion formed 25 at right angles to and intersecting the nearly- vertical aperture through which the screw-bolt passes.

My invention is an improvement on the invention set forth in Letters Patent No. 170,462, 30 issued to me.

My invention has for its object to dispense 35 with the aperture in the rear of the foot portion for the reception of the nut, thus simplifying the construction; and it consists in a boot-tree in which the foot portion is provided 40 with a tubular nut or threaded sleeve for the screw-bolt to engage with, this nut being introduced within the aperture through which the screw-bolt passes, and being secured in 45 place and prevented from being turned or withdrawn by a pin driven through it from the outside.

To enable others skilled in the art to understand and use my invention, I will proceed to 45 describe the manner in which I have carried it out.

In the said drawings, A represents the upper portion or leg of the boot-tree, which is 50 cut away at its lower end for the reception of the rear end of the foot B, the two portions being secured together by a long bolt or rod, 55 a, which passes through the aperture b in the leg portion and enters the aperture c in the foot portion, the lower end of the bolt being

provided with a screw-thread, which engages 55 with a tubular nut or threaded sleeve, d, which is of such diameter as to snugly fit the aperture c, and, after being introduced therein and forced down into place, is secured by means of a pin, e, driven from the outside through 60 holes in the sides of the nut, by which means it is prevented from turning around within the aperture c, and also from being withdrawn by the upward strain of the screw-bolt a; and by thus employing a tubular nut, d, applied 65 to the foot portion, as above described, instead of an ordinary flat nut driven into an aperture or recess formed in the rear end of the foot-piece at right angles to the aperture c, as heretofore, the construction of the tree 70 is simplified and its cost reduced, while the liability of the nut being turned or otherwise displaced by being suddenly struck by the lower end of the connecting-bolt when inserted, as sometimes occurs with the old construction, is entirely avoided, the tubular nut 75 d being always in the proper position to receive the screw-thread at the lower end of the bolt a. Furthermore, this tubular nut serves to strengthen that part of the foot-piece 80 through which it passes.

If desired, the aperture c and tubular nut d may extend entirely through the foot portion, the tubular nut being provided with a flange or head lying flush with the sole or bottom of 85 the foot portion, which would afford additional resistance against any tendency of the screw-bolt to withdraw the nut.

What I claim as my invention, and desire to 90 secure by Letters Patent, is—

A boot-tree for vulcanizing rubber boots having the foot portion B provided with an elongated tubular nut or internally-threaded sleeve, d, within the aperture c, and secured by a pin, e, and the rear end beveled from the 95 center toward each side, as seen at f 6 6, and a leg portion, A, having a correspondingly-inclined surface for the rear of the foot-piece to rest against, and provided with a securing-screw, a, the whole constructed and arranged 100 as set forth.

Witness my hand, this 15th day of November, 1879.

GEORGE W. BADGER.

In presence of—

P. E. TESCHEMACHER,
W. J. CAMBRIDGE.
